UNITED STATES PATENT OFFICE.

CHARLES W. SHEVLIN, OF CHICAGO, ILLINOIS.

CONTAINER.

1,106,004.

Specification of Letters Patent.

Patented Aug. 4, 1914.

Application filed December 5, 1912. Serial No. 735,022.

To all whom it may concern:

Be it known that I, CHARLES W. SHEVLIN, a citizen of the United States, and a resident of Chicago, in the county of Cook and State of Illinois, have invented a new and useful Container, of which the following is a specification.

My invention relates to containers made of paper or tissue which is infused or impregnated with a suitable substance to render it impervious to air or moisture or liquids so that the container may be either used for containing liquids, or for containing other substances free from the action of exterior air or moisture or liquids.

The use of paraffin as a substance for treating paper to render it impervious to water is well known. In order, however, to secure the best results the substance of the tissue must be thoroughly homogeneously infused or impregnated with the material and not merely coated with it, as a more or less thorough coating not having the bonding action of the tissue is liable to checking or cracking which, of course, spoils its integrity. It is known, also, that when paper is impregnated with paraffin it is weakened, and even the harder varieties of paraffin have a more or less greasy character which tends to collect dust and will interfere with the labeling of the container with either printing directly upon it, or by means of a label designed to be secured thereto. It may or may not be known, but, nevertheless is a fact, that an article cannot be successfully both glued and impregnated with paraffin, for the reason that glue requires for its successful action both in its own substance and in the substance to which it is applied a certain amount of moisture, while the action of paraffin is to drive out all the moisture. It is known that a paper impregnated with paraffin cannot be successfully glued, and when an article which has been previously glued is impregnated with paraffin the glue is caused to let go.

In view of the above physical conditions my present invention has for its object the provision of a container which will embody all the advantages to be derived from an impregnated liner, together with an unimpregnated outer casing.

Another, and very essential object, is the provision of both the outer casing and liner in one integral strip, thus simplifying the construction.

I attain the above objects by the structure illustrated in the accompanying drawings, in which—

Figure 1 is a central section through a completed container; Fig. 2 is a perspective view of the outer casing or first lap of the container, temporarily held in shape by staples, the liner or remaining impregnated strip being shown spirally wound and partially withdrawn, and Fig. 3 is a plan view of the container blank.

Similar reference numerals designate similar parts throughout the several views.

Reference numeral 4 designates the entire continuous blank from which the walls of the body of my container are made, while the numeral 5 designates the portion of the blank which forms the outer casing, and which is not impregnated; and 6 designates the liner or the other portion of the blank which is homogeneously impregnated with a material suitable for the use to which the package is to be put. After the portion 6 of the blank 4 has been impregnated, the blank is then rolled up with the portion 5 on the outside. This portion or outer lap, is held temporarily in position by suitable staples 7. The lining 6, or remaining portion of the blank, due to its expansiveness resulting from coiling, will tend to expand and contact with the inner surface of the outer wall 5. This tendency, however, should be supplemented by a suitable former or mandrel, the action of which will secure a uniform and perfect contact between the layers forming the liner 6 and the outer casing 5. When paraffin is used as the impregnating material the container is then heated, and the outer and inner casings are caused, by the known properties of paraffin, to adhere together, forming a solid wall, the inner portion being homogeneously impregnated while the outer portion remains only slightly coated upon its inner surface, and unimpregnated, thus rendering the package walls water-proof, while at the same time, the outside walls thereof will retain their original strength and be suitable for any purpose for which a container of ordinary paper may be used. Interiorly opening beads 8 are turned in the said walls, a suitable distance from the top and from the bottom, said beads forming interior grooves for the two end members 9 and 10, the bottom end 10 being a solid disk, while the other end 9 is ring shaped to provide an

annular shoulder or flange 11 so that a disk 12 may be placed thereon to form a top closure or cover for the package. The ends of the body walls are then turned inwardly as 5 at 13, thus forming internal shoulders abutting the ends 9 and 10.

Having described my invention what I claim as new and desire to secure by Letters Patent, is:—

- 10 1. A method for forming containers comprising the thorough and homogeneous infusion and impregnation of a strip of fibrous material with a cementitious moisture resisting material, the formation of a cylindrical shell, the insertion of said infused strip within said shell, and the pressing of said infused strip so that it will contact with and adhere to the walls of said shell.
- 20 2. A method for forming containers comprising the thorough and homogeneous infusion and impregnation of a strip of fibrous material with wax, the formation of a cylindrical shell, the insertion of said waxed strip within said shell, and the pressing and heating thereof so that it will contact with and adhere to the walls of said shell.
- 25 3. A method for forming containers com-

prising the thorough and homogeneous infusion and impregnation of a portion of a strip of fibrous material with a cementitious 30 moisture resisting material, the formation of a cylindrical shell from the unimpregnated portion of said strip, the insertion of the impregnated portion of said strip within said shell, and the pressing thereof so that 35 it will contact with and adhere to the walls of said shell.

4. A method for forming containers comprising the thorough and homogeneous infusion and impregnation of a portion of a 40 strip of fibrous material with wax, the formation of a cylindrical shell from the unimpregnated portion of said strip, the insertion of the waxed portion of said strip within said shell, and the pressing and heating thereof so that it will contact with and adhere to the walls of said shell.

In testimony whereof I affix my signature in the presence of two witnesses.

CHARLES W. SHEVLIN.
